United States Patent Office

Des. 225,419

Patented Dec. 12, 1972

225,419

GOLF CLUB

Truett P. Mills, 1700 2nd Ave., Tuscaloosa, Ala. 35401

Filed Sept. 23, 1970, Ser. No. 25,155

Term of patent 14 years

Int. Cl. D21—02

U.S. Cl. D34—5

FIG. 2

FIG. 3

FIG. 1 is a side view of a golf club according to the present design.

FIG. 2 is a top view of a portion of the golf club shown in FIG. 1.

FIG. 3 is a side view of a portion of a golf club as shown in FIG. 1.

The characteristic feature of my design resides in the particular club head form with no hosel in combination with the shaft as shown.

I claim:

The ornamental design for a golf club, substantially as shown and described.
